Primary Examiner — T Chase Nelson*Assistant Examiner* — Kelly L Gross(74) *Attorney, Agent, or Firm* — Nixon & Vanderhye PC(57) **CLAIM**

The ornamental design for a dialysis apparatus, as shown and described.

DESCRIPTION

Fig. 2.1 is a perspective view of a dialysis apparatus according to my new design;

Fig. 2.2 is a left view thereof;

Fig. 2.3 is a right view thereof;

Fig. 2.4 is a front view thereof;

Fig. 2.5 is a back view thereof;

Fig. 2.6 is a top view thereof; and

Fig. 2.7 is a bottom view thereof.

The broken lines show portions of the dialysis apparatus that form no part of the claimed design.
